UNITED STATES PATENT OFFICE.

WILLIAM V. MEYER, OF CHICAGO, ILLINOIS.

TIE FOR UMBRELLA-RIBS.

1,263,787.

Specification of Letters Patent. Patented Apr. 23, 1918.

Application filed June 22, 1916. Serial No. 105,152.

To all whom it may concern:

Be it known that I, WILLIAM V. MEYER, a citizen of the United States, residing at Chicago, in the county of Cook and State of Illinois, have invented certain new and useful Improvements in Ties for Umbrella-Ribs, of which the following is a specification.

My invention relates more particularly to means for holding the ends of the ribs in close contact with the umbrella rod immediately below the handle and it consists in a simple and inexpensive device for this purpose which may be readily applied to any ordinary form of umbrella, will not readily become detached therefrom, will securely hold the ribs in place when closed and will not become entangled with the ribs or braces of the umbrella in opening the same.

In the accompanying drawing Figure 1 shows the upper portion of an umbrella of ordinary design with my invention applied thereto but open or unfastened so that the ribs are free to separate or assume their usual position; Fig. 2 is a similar view but with the tie device closed and maintaining the ribs against the umbrella rod; Fig. 3 is a plan of the tie detached on a somewhat enlarged scale as compared with Figs. 1 and 2; and Fig. 4 is an edge view on a similar scale of the detached tie.

The body of the tie is formed of a ribbon

5 of textile or other suitable fabric one end of which 6 is bent back upon the body of the tie to form a loop which is made so small as to pass over the usual ball end 8 35 of an umbrella rib with difficulty so that when it is slipped thereon it will not be accidentally detached. One member 9 of a snap fastener is secured close to the loop and preferably upon the doubled portion of 40 the tie and the other member 10 of the snap fastener is secured to the other end of the tie.

The tie is applied to any one of the ribs of an umbrella by simply forcing the loop 45 over the ball thereof when the tie is ready for use. In order to hold the ribs together the tie is simply carried about them and the snap catch closed. Various modifications may be resorted to, such as in the material of 50 the tie or the nature of the fastener, without departing from my invention in its broader aspect.

I claim:

An umbrella comprising the usual ribs, 55 and a tie, one end of which is tightly looped about the end of one of the ribs and which is provided with a snap catch, one of the members of which is attached to one end of the tie and the other member to the other 60 end thereof.

WILLIAM V. MEYER.
